US0D1052550S

(12) **United States Design Patent** (10) Patent No.: **US D1,052,550 S**
(45) Date of Patent: ** *Nov. 26, 2024

(54) **TELEVISION RECEIVER**

(71) Applicant: **LG ELECTRONICS INC.**, Seoul (KR)

(72) Inventors: **Yongseok Kim**, Seoul (KR); **Jiwon Park**, Seoul (KR)

(73) Assignee: **LG ELECTRONICS INC.**, Seoul (KR)

(*) Notice: This patent is subject to a terminal disclaimer.

(**) Term: **15 Years**

(21) Appl. No.: **35/518,834**

(22) Filed: **Oct. 31, 2022**

(80) **Hague Agreement Data**

Int. Filing Date: **Oct. 31, 2022**

Int. Reg. No.: **DM/224721**

Int. Reg. Date: **Oct. 31, 2022**

Int. Reg. Pub. Date: **Nov. 3, 2023**

(30) **Foreign Application Priority Data**

Jun. 2, 2022 (KR) 30-2022-0022095

(51) **LOC (14) Cl.** **14-03**

(52) **U.S. Cl.**

USPC **D14/125**; D14/132; D14/134

(58) **Field of Classification Search**

USPC D14/125, 126, 129, 133, 496; D3/273, D3/274, 276, 900

CPC ... H05K 5/00; H05K 5/03; H04N 5/64; G06F 1/1601; G06F 1/1603; G06F 1/1605; G06F 1/1637

See application file for complete search history.

(57) **CLAIM**

The ornamental design for a television receiver as shown and described.

DESCRIPTION

1.1 : Front perspective

1.2 : Rear perspective

1.3 : Front

1.4 : Back

1.5 : Left

1.6 : Top

1.7 : Bottom

1.11 : Reference

The claimed design is a television receiver in which the display unit and the case are integrated into one body; the right side view is omitted because it is a mirror image of the left side view; reproduction **1.11** is a reference view showing the state of use with stand; the broken lines indicate portions

(Continued)

of the article that form no part of the claimed design; the broken lines shown in reproduction 1.11 illustrate environmental structure and form no part of the claimed design.

1 Claim, 8 Drawing Sheets
